UNITED STATES PATENT OFFICE.

ARTHUR COWEN, OF NEW YORK, N. Y., ASSIGNOR TO JOHN H. WILSON CO., INC., OF NEW YORK, N. Y., A CORPORATION OF NEW YORK.

DESIGN FOR A CIGARETTE CASE.

Application filed January 26, 1926. Serial No. 16,281. Term of patent 3½ years.

To all whom it may concern:

Be it known that I, ARTHUR COWEN, a citizen of the United States, residing at New York city, in the county of New York and State of New York, have invented a new and original Design for a Cigarette Case, of which the following is a specification, reference being had to the accompanying drawing, forming part thereof, in which:

Fig. 1 is a perspective view of the cigarette case, showing my new design and showing the same closed;

Fig. 2 is a perspective of the same showing the article opened.

I claim:

The ornamental design for a cigarette case as shown.

ARTHUR COWEN.
